UNITED STATES PATENT OFFICE.

GUS JORDAHL, OF PALM BEACH, FLORIDA.

DEVICE FOR USE IN LEARNING TO SWIM.

1,368,937.

Specification of Letters Patent. Patented Feb. 15, 1921.

Application filed April 28, 1920. Serial No. 377,271.

To all whom it may concern:

Be it known that I, Gus JORDAHL, a citizen of the United States, and a resident of Palm Beach, in the county of Palm Beach 5 and State of Florida, have invented certain new and useful Improvements in Devices for Use in Learning to Swim, of which the following is a specification.

My present invention relates generally to 10 devices for use in learning to swim and more particularly to an inflatable device adapted to encircle the body and to be positioned in such manner as to preclude accidental displacement.

15 More particularly my present invention aims to improve former devices of this character by providing for more ready tying of the ends of the tube, which tying serves the double function of retaining air in the tube 20 and properly holding the tube around the body.

In the accompanying drawing illustrating my invention and forming a part of this specification,

25 Figure 1 is a perspective view illustrating the practical application of my invention, and

Fig. 2 is a detail perspective view of my invention deflated.

30 Referring now to these figures and particularly to Fig. 2 my invention proposes an elongated flexible tube 10 whose diameter for its major portion provides sufficient internal area to hold a desired amount of air 35 for proper support of the body in the water. This tube is open ended or is at least open at one end 11 even though its opposite end

12 may be closed, and is in accordance with my invention provided with reduced or narrowed end portions 13 which facilitate the 40 tying of these ends as indicated at 14 in Fig. 1, so as to hold the tube around the body of the user. Tying of the ends serves the double function of securing the tube in effective position and closing its ends against 45 the egress of air which is previously forced into the body of the tube through its open end 11.

I may thus form the body of a considerable width, adapting it to hold air in ample 50 quantity for practical purposes, and still provide for ready tying of its ends in tight non-leaking relation.

In practice the tube as a whole may be formed from a single piece of any suitable 55 material such as a plain fabric which will become non-leaking when wet, a rubberized cloth, or rubber, and in fact it is to be understood that any material suitable for the purpose may be utilized.

60 I claim:

A device to be used in learning to swim consisting of a long flexible open ended tube adapted to encircle the body of a wearer and having a body portion of sufficient width to 65 form an internal air space of ample proportions, the ends of the tube being reduced at opposite sides of the body whereby when the latter is blown up its said ends may be effectively tied and serve the double 70 purpose of holding the device in place on the wearer and retaining the air in the body.

GUS JORDAHL.
